UNITED STATES PATENT OFFICE.

GEORGE A. LEIP, OF LEADVILLE, COLORADO.

HAIR-TONIC.

SPECIFICATION forming part of Letters Patent No. 285,045, dated September 18, 1883.

Application filed July 17, 1883. (No specimens.)

To all whom it may concern:

Be it known that I, GEORGE A. LEIP, a citizen of the United States, and a resident of Leadville, in the county of Lake and State of Colorado, have invented a new and useful compound of vegetable matter for the preservation, growth, and renewal of human hair; and I do hereby declare that the following is a full and exact description thereof.

10 The nature of my invention consists in the preparation of onions, sage, and potatoes by steeping and straining the liquid product or residuum thereof, and applying the same to the human head where the same has become bald or the hair is falling out, the same being rubbed into the scalp by the hands.

15 I make my compound in the following proportions: To one gallon of boiling water I add one pound of onions, one and one-half pound of potatoes, and three-quarters of a pound of sage. After the same has steeped one hour in a suitably-covered vessel, I strain the contents through canvas or any other proper material, and, after cooling, the composition is ready for use. The potatoes should not be peeled, as thus far in my experiments I find they contribute better results in their natural state. The odor of onion in this compound may be neutralized by the addition of any of the standard perfumes; but I prefer to use the prepa-

ration with the three ingredients, as set forth. In using the compound the scalp should be previously vigorously excited by a stiff hair-brush, and during its use the head should not be washed. The surrounding hair should be 35 closely clipped and the compound well rubbed in by the fingers or hands, say, three times a day; though I believe if applied more frequently the desired results will be more quickly attained. Exposing the head to sunshine during the 40 treatment will prove beneficial, and the application should be daily for about two months before positive improvement in the hair-growth can be expected, though in some cases it may be sooner noticed. No injury can result from the 45 use of my compound, as it contains no chemical ingredient.

I am aware that sage has been heretofore used in hair-tonics, likewise onions, as shown by Patents Nos. 112,749 and 129,810, and such 50 by themselves I do not claim; but

What I do claim as my improvement is—

The hair-tonic hereinbefore described, consisting of an infusion of potatoes, onions, and sage, in substantially the proportions stated. 55

GEO. A. LEIP.
